UNITED STATES PATENT OFFICE.

MARTIN C. BURT, OF CHICAGO, ILLINOIS.

TELEPHONE.

SPECIFICATION forming part of Letters Patent No. 754,968, dated March 22, 1904.

Application filed March 17, 1903. Serial No. 148,204. (No model.)

To all whom it may concern:

Be it known that I, MARTIN C. BURT, a citizen of the United States, residing at Chicago, in the county of Cook and State of Illinois, have 5 invented certain new and useful Improvements in Telephones, of which the following is a specification, reference being had therein to the accompanying drawings.

This invention relates to an improvement in 10 telephones and is embodied in the construction and arrangement of parts presently to be described, and defined in the claims.

The object of the present invention is largely 15 and primarily to produce a "telephone," by which term it is to be understood that the same applies to the receiver or transmitter wherein a multiplicity of magnets can be employed to vary or modify the magnetic strength or effect on the diaphragm, and in 20 this connection I have shown a telephone-receiver embodying the invention, but have had more particularly in mind the illustration of a transmitter embodying the general principles of the invention which are largely susceptible of use in other well-known forms of 25 magneto-telephones.

In the accompanying drawings is shown a 30 phone embodying the invention; but it is to be understood that various alterations and changes can be made without departing from the invention.

Figure 1 is a side elevation showing the 35 switch member and the receiver-supporting arm, the latter being in a position directly under the mouthpiece of the transmitter. Fig. 2 is a top plan view showing the receiver with its arm positioned at right angles to that shown in Fig. 1. Fig. 3 is a sectional elevation through the transmitter.

40 A designates a base; B, the standard of a "desk-phone." The standard carries the forked receiver-arm D. D' designates the receiver, and E the transmitter.

The internal construction of the transmitter 45 is conveniently in the form of a series of ring magnets F F' F'', having hollow cores and a portion only thereof surrounded by the wire wrapping. These cores or magnets are separated from each other by insulator-blocks 50 f and are carried on an insulated plate G, se-

cured to the rear of the transmitter. They are insulated one from the other, so that the energizing of one will not affect the other, the insulating material being indicated at f'. The forward ends of the hollow cores are projected forward and perforated for venting purposes to prevent undue heating, and the perforated portions are so positioned as to be out of contact with each other, leaving a free space for the circulation of air therebetween. 55

Each magnet is coupled up with suitable circuits, (designated at H H' H'' H'''), the former being connected with a suitable standard h and the latter three with a switch-plate h' and the respective circuits being connected, respectively, with the magnets in the transmitter. 60

J designates a switch-lever pivoted on the standard h and having a sector or curved extension at its upper end, on the extreme end of which is placed the switch-handle. This 70 switch has close contact with the part h' and is designed to project successively over the terminals of the wires H', H'', and H''', thereby closing the main-line circuit through one or more of the magnets F F' F'', thereby securing greater or less magnetic force in the transmitter. 75

K designates the diaphragm of any approved form of construction, carrying the armatures k k' k''. These armatures are 80 conveniently of ring formation to correspond with the magnetic cores, as shown.

The construction of the phone as above described is such that when desired the operator by the switch, which may be conveniently located, can of his own volition increase or decrease the magnetic strength or extent of magnetic influence on the diaphragm, a condition which is often necessary in connection with different conditions of weather or variations in distance. 85 90

As above stated, these various features of the telephone described can be modified without departing from the invention.

Having thus described the invention, what 95 is claimed as new, and desired to be secured by Letters Patent, is—

1. In a telephone, the combination with a diaphragm carrying armatures, of a series of 100 magnets for the armatures, circuits leading to

the magnets, and a switch arranged in operative position relative to the telephone and adapted for closing the circuits through one or more of the magnets.

- 5 2. In a telephone, the combination with a diaphragm having a series of ring armatures thereon, of a series of magnets arranged respectively one within the other and having their cores adjacent to said armatures, circuits connected with the said magnets, and a single switch designed to close the circuits of one or more of the magnets.
- 10 3. In a telephone, the combination with a

diaphragm, of a series of magnets having hollow cores arranged one within and insulated 15 from each other and the forward ends of which are perforated, armatures on the diaphragm, circuits leading from the magnets, and a switch for the circuits.

In testimony whereof I affix my signature in 20 presence of two witnesses.

MARTIN C. BURT.
